UNITED STATES PATENT OFFICE.

GEORGE HENRY ELWELL, OF DETROIT, MICHIGAN.

DOOR LATCH.

Application filed February 18, 1921. Serial No. 446,106.

To all whom it may concern:

Be it known that I, GEORGE HENRY ELWELL, a citizen of the United States, residing at Detroit, in the county of Wayne and State of Michigan, have invented certain new and useful Improvements in Door Latches, of which the following is a specification.

My invention relates to improvements in door latches and more particularly to that class of latches employing a bolt for positive and anti-rattle engagement with the keeper.

The objects of my invention are to provide a latch bolt fully adapted to the elasticity of motor car bodies and like uses; to provide a latch bolt that in locked position is adapted to maintain a fixed relation with its keeper but does not depend upon its relative position to the keeper for its closing operation; and to provide a bolt advancing spring means the operative tension of which may be removed from the bolt to operate a door opening member.

With these and other objects in view, as will more fully hereinafter appear, the invention consists in certain novel features of construction and arrangement of parts hereinafter described, illustrated in the accompanying drawing and particularly pointed out wherein patentable novelty is claimed for certain features of the device, it being understood that within the scope of what hereinafter thus is claimed various changes in form, proportion, size and minor details of the construction can be made without departing from the spirit or modifying any of the advantages of the invention.

The following is the description of an embodiment of my invention, reference being had to the accompanying drawing in which

Figure 1 is a side elevation of the device with inner casing shown in dotted line;

Figure 2 is a face view of the preceding figure;

Figure 3 is a side elevation of a modification of the device, the mechanism being shown in dotted line where covered by inner casing;

Figure 4 is a detailed view of bolt head in fixed relation to keeper; and

Figure 5 is a detailed view of spring lever and helical spring.

Referring more particularly to the drawing:—Casing "1" is a base-plate having face "2" formed by bending said base-plate, as

shown in Figures 1, 2, 3 and 4. Perforation "3" in face "2" together with slot guide "23" in inner casing "4" attached to casing "1" provides the guiding means for bolt head "6" and slotted bolt arm "7", respectively, permitting bolt "5" to advance beyond said face "2". Casing "1" is provided with proper bearings for shaft "16" journalled thereto and extending parallel with said face "2", as shown in Figures 1, 2 and 3. Casing "1" is also provided with perforations "27" and "28" to receive and provide bearings for the end of spindle socket shaft "22" and spring lever shaft "14", respectively.

Inner casing "4" is riveted to casing "1" and is provided with perforations "27A" and "28A" to receive and provide bearings for the other end of each of said shafts "22" and "14", respectively. Said inner casing "4" is also provided with rolled section "25", said section being rolled around crank shaft "13" providing a bearing within which said shaft "13" may partially rotate with the crank end "18" of said shaft "13" projecting through slot "26" with which said face "2" of casing "1" is provided, as shown in Figure 2.

Said spindle socket shaft "22" is provided with square perforation "12" to receive a spindle, and said shaft "22" provides a bearing for cam lever "11" mounted thereon and keyed thereto so as to make only a shifting movement on said bearing before rotating said shaft "22". Said cam lever "11" is provided with arm "8" adapted for engaging the rear surface of said bolt head "6" and is also provided with arm "24" for operative engagement by cam end "17" of rotary shaft "16".

Spring lever shaft "14" is provided with cam lever "9" adapted for engagement by cam end "15" of crank shaft "13", and said shaft "14" is also provided with a slot "29" adapted to hold the inner terminal "19" of helical spring "20" mounted on said spring lever shaft "14", as shown in Figure 5. The outer terminal "21" of said spring "20" being adapted to engage the rear surface of arm "8" of cam lever "11", as shown in Figures 1 and 3.

Coiled spring "10" is seated in both the slot of bolt arm "7" and the slot bolt guide "23" in inner casing "4", which slots normally superimpose, the rear end of said spring "10" engaging bolt arm "7" and

the forward end engaging check "30" with which inner casing "4" is provided and which lies in slotted arm "7" of bolt "5", said spring "10" normally holding bolt "5" in a retracted position, as shown in Figure 1.

In operation the crank lever "18", upon closing the door, engages the door-frame, preferably in the rabbet, and, as the door closes, said crank lever "18" is operated 10 backwardly forcing the cam end "15" of crank shaft "13" down upon spring cam lever "9", slightly winding spring "20" and creating a tension on its outer terminal "21" sufficiently great to move forwardly 15 lever cam arm "8" of spindle socket shaft lever "11". As this cam arm "8" moves forwardly, it forces, against the tension of spring "10", bolt "5", with which it is engaged, to an advanced position, as shown in Figure 3, into its keeper "31". The keeper "31" is preferably of such construction as to permit the bolt head "6" to fixedly lodge 20 therein allowing the bolt head "5" to advance to such an extent only as the fluctuating or fixed relative positions of face "2" of casing "1" and the keeper will allow, as shown in Figure 4. There are two selected ways in which the door may be opened. Rotary shaft "16" may be rotated and thereby 25 operate backwardly said lever cam arm "8" or, by means of a spindle inserted in perforation "12" of spindle socket shaft "22", said lever cam arm "8" may be similarly operated. As said lever cam arm "8" is thus, 30 in either way, forced backwardly, spring terminal "21" is also forced with it, and the bolt advancing spring tension having been removed from off bolt "5", coiled spring "10" immediately operates bolt "5" to a retracted position. The forcing backwardly 35 of spring terminal "21" reverses the operative tension of said spring "20" to its inner terminal "19", forcing spring cam lever "9" upwardly against cam end "15" of crank shaft "13", turning said shaft "13" and operating forwardly said crank "18" against the door-frame and automatically opening 40 the door as bolt "5" is retracted.

Said crank "18" should preferably be protected by a proper shield to prevent the 45 catching of clothing thereon.

A modification of the above construction is shown in Figure 3. The crank lever "13" is omitted and the spring lever "9" is of such 50 form and construction as to project through slot "26" in face "2" of casing "1" and thus said lever "9" is adapted for a lever latch operation with a striker-plate. Said striker-plate to operate this modified construction 55 must be of the well-known type of striker-plates having the striker portion projecting, as it were, from between the door face and the face of the door-frame when the door is closed, the upper part of said striker portion having an inclined edge capable of lift-

ing said lever 9, as shown in Figure 3, when engaged by that lever upon the closing of the door. The slot, however, with which such a striker portion is usually provided should be omitted, the lifting function of such striker portion only being utilized in connection with this modification.

In place of rotary shaft "16" a swinging lever might be made to operate bolt "5".

What I claim is:

1. In a door latch having a proper casing and comprising a bolt slidably mounted in said casing; spring means adapted to advance and maintain said bolt in an advanced position projecting beyond the face of said casing; manually operative means for removing and holding the tension of said spring means from off the bolt; and spring means counteracting with said first spring means and adapted to retract said bolt automatically on the removal of said first spring means.

2. In a door latch having a proper casing and comprising a bolt slidably mounted within said casing; a spring mechanism adapted to advance and maintain said bolt in an advanced position projecting beyond the face of said casing; manually operative means to remove the tension of said spring mechanism from off said bolt; spring means adapted to retract said bolt automatically on said removal of the tension of said spring mechanism; and means with which the free edge of the door is provided for automatic yielding engagement with a door-frame and adapted to re-engage said spring mechanism with the bolt upon closing the door.

3. In a latch for vehicle doors the combination with a proper casing; of a longitudinally movable bolt, slidably mounted within said casing; of counteracting spring means exerting spring tensions on said bolt in both longitudinal directions; and of a rotatable shaft and connections between said shaft and the bolt advancing spring tension whereby with the rotation of said shaft the bolt advancing spring tension is removed from said bolt permitting the spring tension in the opposite direction to operate said bolt to a retracted position.

4. The combination with a door-frame and a door hinged thereto; of a proper casing; of a bolt, with which said casing is moveably provided, for latching said door in a closed position to said frame; of a door opening means with which said casing is provided at the free edge of said door and which means is normally adapted to hold said door open; and of spring actuated means normally adapted to hold said door opening means in normal position when said door is open and to advance and maintain said bolt in a latching position when said door is closed, said spring actuated means comprising a helical spring all of the coils

- of which lie substantially in the same plane with the inner terminal of said spring fixedly engaged with a lever pivotally mounted on said casing, said lever being operative 5 ly provided with said door opening means and the outer terminal of said spring directly providing the bolt advancing spring tension on said bolt when said door is closed against said door opening means.
- 10 5. In a door latch having a proper casing and comprising a door opening device with which the face of said casing is provided; a bolt slidably mounted in said casing; a helical spring device exerting from 15 both terminals of said spring a spring tension in opposite directions and adapted to operatively engage said door opening device and said bolt; and means for retracting said bolt while the door is closed; whereby said 20 spring device operates only said bolt to an advanced position projecting beyond the face of said casing when the door is closed against said door opening device and operates only the said door opening device to 25 open door position when said bolt is retracted permitting said door opening device to open the door, said bolt remaining in a retracted position while the door remains open.
- 30 6. In a door latch having a proper casing; a longitudinally movable bolt slidably mounted within said casing; a laterally movable door opening member with which the face of said casing is provided; a helical 35 spring mechanism adapted normally to remain idle when the door is open, said spring mechanism also being adapted to exert from both terminals of said helical spring an alternate tension first on said 40 bolt, when the door is closed against said opening member, and then on said door opening member when said bolt is retracted while the door remains closed; and manually operative means for retracting said bolt 45 while the door is closed.
7. In a door latch having a proper casing; a bolt slidably mounted within said casing, a door opening member with which the face of said casing is provided; a helical 50 spring mechanism adapted normally to remain idle when the door is open, said spring mechanism being adapted to exert from both terminals of said helical spring an alternate tension first to advance said bolt when the 55 door is closing against said opening member and then to operate said door opening member when said bolt is retracted while the door is in a closed position; manually operative means for removing said tension of 60 said helical spring from said bolt when the door is closed; and spring means for retracting said bolt when said bolt advancing spring tension is removed from said bolt.
8. In a door latch comprising a proper
- casing having a face provided with a bolt 65 passage; a bolt slidably mounted within said casing, said bolt being provided with a head adapted for projection beyond the face of said casing; a door opening member with which the face of said casing is provided; a 70 spring device exerting from both terminals of one helical spring, all of the coils of which lie substantially in the same plane, spring tension in opposite directions, one of said spring terminals operatively adapted 75 to engage and advance said bolt and the other of said spring terminals being adapted to directly engage said door opening member; means for retracting said bolt while the door is closed; and a keeper adapted to receive said head, to check the full advancement of said bolt and to maintain a fixed non-rattling relation with said head while the door remains fully closed.
9. In a door latching device comprising 85 a door latch and a striker-plate, said door latch comprising a proper casing having a face; two independently moveable elements moveably mounted within said casing and operating beyond said face, each of said 90 elements adapted to engage said striker-plate in right angle directions of one element to the other; spring means with which each of said two elements is provided; and manually operative means adapted to disengage said elements in their engagements with said striker-plate.
10. In a door latching device comprising 95 a door latch and a striker-plate, said door latch comprising a proper casing having a face; two independently moveable elements moveably mounted within said casing and each element operating beyond the face of said casing in right angle converging directions one to the other; a spring means by 100 which each of said two elements is spring-pressed, one of said elements by one terminal and the other of said elements by the other terminal of the same spring; and manually operative means for disengaging said 105 two elements from their engagements with said striker-plate; whereby said two elements are adapted to automatically engage said striker-plate by a movement of one element which is right angle to the movement 110 of the other element upon the closing of the door, the said movements of said elements engaging said striker-plate occurring in sequence and the element first engaging said 115 striker-plate automatically winding said 120 spring and operating said other element to its engaging position.

In testimony whereof I have affixed my signature, in presence of two witnesses.
